UNITED STATES PATENT OFFICE.

GERALD MASON VAN DYKE, OF TIENSIN, CHINA, ASSIGNOR OF ONE-THIRD TO THOMAS J. McNALLY AND ONE-THIRD TO HUGH K. MACDOUGALL, BOTH OF TIENSIN, CHINA.

CLOCK CALENDAR.

Application filed August 4, 1924. Serial No. 730,051.

This invention relates to clock calendars and has particular reference to a calendar secured to the hour hand of the clock or an extension thereof, which calendar is 5 equipped with means for registering the date and day of the week simultaneously with the rotation of the hour hand about the face of the clock.

The primary object of this invention is 10 to equip a calendar with an indicating means and gravity actuated mechanism whereby the date, day of the week and time will be accurately and positively presented for observation as the hour hand or its extension 15 is actuated by the clock mechanism.

A further object of this invention is to 20 provide a plurality of date discs, which may be suitably fastened to the permanent face of the calendar whereby a complete calendar will be displayed, with the discs so positioned and arranged that the first day of any succeeding month will accurately follow the last day of the preceding month thus eliminating the necessity of adjusting 25 the calendar.

Other objects are to provide a novel clock calendar arrangement that is economical to manufacture, positive in operation and a 30 calendar arrangement which is readily applicable to standard types of clocks without materially altering the construction of the same.

Other objects and advantages will be apparent during the course of the following 35 description.

In the accompanying drawings forming a part of this specification, and in which like numerals are employed to designate like parts throughout the same,

40 Figure 1 is an elevation of a clock face showing my improved calendar secured thereto,

Figure 2 is a diagrammatic view disclosing 45 twelve discs that may be substituted for the permanent face of the calendar,

Figure 3 is an enlarged rear view of the back of the calendar showing the mechanism for operating the same,

Figure 4 is an enlarged transverse vertical section through the calendar, the view 50 being taken on the line 4-4 of Figure 3, and

Figure 5 is a side elevation of the strip which is secured to the hour hand.

In my co-pending application filed March 25th, 1924, Serial Number 701,764, I have also devised means for registering the day and date of the week simultaneously with the rotation of the hour hand about the face of the clock, but in this device it was necessary to employ a cog wheel at one side of the calendar which appreciably limited the size of the calendar.

In the present clock calendar, I am able to employ an exceedingly large size calendar without interfering, in any respect, with any part of the clock mechanism or the reading of the clock as long as the diameter of the calendar is not greater than the distance from the shaft carrying the hour hand 55 to approximately the periphery of the clock face.

In my former invention it was also necessary to adjust the calendar at the end of the period of one month, but in the present device the step of adjustment can be eliminated by the provision of a circular block 60 of dates detachably fastened to the permanent face of the calendar. It will be observed that I have provided a complete calendar which appreciably limited the size of the calendar.

70 In the present clock calendar, I am able to employ an exceedingly large size calendar without interfering, in any respect, with any part of the clock mechanism or the reading of the clock as long as the diameter of the calendar is not greater than the distance from the shaft carrying the hour hand to approximately the periphery of the clock face.

In my former invention it was also necessary to adjust the calendar at the end of the period of one month, but in the present device the step of adjustment can be eliminated by the provision of a circular block 75 of dates detachably fastened to the permanent face of the calendar. It will be observed that I have provided a complete calendar which appreciably limited the size of the calendar.

80 In the present clock calendar, I am able to employ an exceedingly large size calendar without interfering, in any respect, with any part of the clock mechanism or the reading of the clock as long as the diameter of the calendar is not greater than the distance from the shaft carrying the hour hand to approximately the periphery of the clock face.

In my former invention it was also necessary to adjust the calendar at the end of the period of one month, but in the present device the step of adjustment can be eliminated by the provision of a circular block 85 of dates detachably fastened to the permanent face of the calendar. It will be observed that I have provided a complete calendar which appreciably limited the size of the calendar.

90 In the present clock calendar, I am able to employ an exceedingly large size calendar without interfering, in any respect, with any part of the clock mechanism or the reading of the clock as long as the diameter of the calendar is not greater than the distance from the shaft carrying the hour hand to approximately the periphery of the clock face.

95 In the present invention I have also devised mechanism so that the calendar will remain in an upright position, at all times, regardless of the angle of the hour hand or its strip, thus making it possible to have all the indicia printed thereon in an upright position, at all times. Thus it will be evident that the calendar can more easily 100 and more readily be read.

105 Referring now to the drawings, the numeral 13 designates the face of a clock which is equipped with the usual minute hand 14 and hour hand 15, the hour hand having secured thereto an attachable strip designated

as a whole by the numeral 15', a detailed description of the strip and its function will be given hereinafter.

Carried in the strip 15' is a pintle 16, which, in turn, supports the calendar mechanism. The calendar embodies in its construction a disc 17 which is carried by the pintle and is free to rotate thereon and is herein referred to as the day disc. This disc 10 is preferably made of thin metal and has arranged on its face and adjacent its periphery and from left to right the days of the week. Likewise mounted on the reduced portion 18 of the pintle is a date disc 19 of 15 a larger diameter than the diameter of the disc 17 positioned in frictional contact with the disc 17, and disposed rearwardly thereof. This date disc 19 has displayed thereon, an arrangement of a plurality of numerals 20 ranging from one to thirty-one, to indicate the various dates of the month and likewise has displayed thereon abbreviations for the various months, which abbreviations are grouped in the columns bearing the dates 25 twenty-eight, twenty-nine, thirty and thirty-one, according to the number of days each month contains.

These abbreviations of the month are so placed for the information of the observer 30 who does not happen to know the days in each particular month.

Mounted rearwardly of the date disc 19 and spaced therefrom and rotatable with the pintle 16 and loosely mounted on the reduced portion 18 thereof, I have provided a wheel 20 equipped with a peripheral ledge 21 and forming in reality an internal gear provided with ninety-eight teeth, the peripheral ledge extending rearwardly so as to 35 cover the external teeth of a second gear wheel 22. It will be observed that this wheel 22 revolves on the enlarged portion of the pintle 16, is spaced from the wheel 20 and rotates with the pintle. This second 40 wheel 22 is equipped with ninety-one teeth which mesh with the teeth of the internal gear. By enlarging the pintle adjacent one end and mounting the wheel 22 thereon I have shifted the center of the wheel 22 a 45 sufficient distance to assure a regular and constant meshing of its teeth with the teeth of the wheel 20.

The numeral 23 designates a small weight element preferably not exceeding one-half 50 ounce in weight, which I propose to make an integral part of the wheel 22. This weight element functions to gravitate constantly downward, and, accordingly, as the hour hand 15 moves to the right (clockwise) 55 the action of the weight moving downwardly causes the wheel 22 to set up a force counter to the way the hour hand is turning. From this action it will be evident that the wheel 20 which carries an indicator 24 60 will be retarded by the counter action and

movement of the wheel gear 22, which retards the speed of the wheel 20 to approximately one-fourteenth of the speed of the hour hand. Thus when the hour hand makes two complete revolutions the wheel 70 20 makes only one-seventh of a revolution and the indicator 24 on the wheel 20 will be carried only one-seventh of the distance around the calendar in twenty-four hours or the distance between the space indicated by 75 the reference characters A and B, which space indicates one day of twenty-four hours. It is to be noted that this indicator 24 revolves in absolute co-ordination with the movement of the hour hand of the clock, at one-fourteenth the speed thereof, thus indicating to the observer at all times, the day 80 of the week and date of the month.

The upright position of the calendar, at 85 all times, regardless of the position of the hour hand is realized by applying a small weight as indicated at 25 on the bottom of the calendar disc 19. This weight is preferably of one-eighth ounce and as the hour hand moves to the right the lower side of 90 the calendar will always gravitate downwardly and cause the calendar face consisting of the discs 17 and 19 to remain in an upright position. The frictional contact between the discs 17 and 19, causes them to 95 assume the same position as before referred to.

Referring now to Figure 5, the rectangular metal strip 15' has integrally formed therewith end clips 26 and 27. These clips are adapted to embrace the hour hand of the clock so as to form a positive connection therewith, and while the strip is here shown attached to the front of the hour hand it is to be understood that it may be 100 readily applied to the back of the hour hand. This strip is provided with a centrally positioned slot 32 adapted to encircle the clock shaft 33, which supports the hour and minute hands. The said strip is likewise provided adjacent its lower extremity with an aperture 34 which strip has fixed thereto the pintle 16.

As shown to advantage in Figure 2, the numeral 35 designates a plurality of dials 110 preferably made of very thin stiff paper and perforated as at 36. These dates are preferably placed one in back of the other with their openings 36 registering and with the disc bearing January as the first of the 115 group and the disc bearing December as the last of the group. They can then be secured to any of the fastening elements indicated as at 37 on the face of the calendar and suspended therefrom. These dials are positioned within the glass covering of the clock face and are so arranged that the first of each succeeding month will be in a similar column to the one which follows the last 120 date in the preceding month and, accord- 130

ingly, the indicator 24 will be in the correct position for each succeeding month and it is only necessary for the care and attention of this calendar to remove on the first of 5 each month, a single dial which represents the preceding month.

It will be observed that in using these dials the dates change their position in each succeeding month, but the days of the week 10 never change and the indicia for both are always in an upright position.

In setting or adjusting the calendar in case the date dials are not used and only the single face of the calendar comprising the 15 discs 17 and 19 are used, the adjustment of the calendar to designate the proper day and date of the week is obtained by placing the operator's finger on the indicator 24 and revolving the indicator thirteen fourteenths 20 of a revolution (clockwise) for each twelve hour period of time that it is desired to set the indicator. Accordingly, if it is desired to set the indicator back twenty-four hours it is only necessary to revolve the indicator twenty- 25 six fourteenths revolution (1 six-sevenths revolutions) to the right (clockwise) for a one-seventh revolution of the indicator equals twenty-four hours. Therefore, for each column (counter clock-wise) that it is 30 desired to set the indicator it is only necessary to rotate the indicator thirteen columns to the right, one and six-sevenths of a revolution. This operation is due to the fact that the wheel 20 has ninety-eight cogs 35 thereon and the wheel 22 has only ninety-one or thirteen-fourteenths as many teeth. Thus when rotating the large wheel 20 thirteen-fourteenths revolutions in either direction the wheel 22 will be rotated exactly one 40 revolution in the same direction and will remain at rest and will also bring wheel 20 to rest at that point due to the weight on the bottom side of wheel 22 which always returns to the same position.

45 For setting the indicator to the right of any given point, it is only necessary to reverse the action above set forth. For any minor corrections of the time piece, it is not necessary to adjust the calendar for when 50 the hour hand is moved to the right or to the left, the indicator 24 will be moved to the right or to the left by action of the weight 23 gravitating constantly downwardly which applies the necessary force on 55 wheel 20 which will cause the indicator to move to its proper position and, therefore, the calendar may be correctly termed "self-adjusting" and "self-correcting".

It is a well-known fact that all ordinary 60 calendars, with few exceptions, have similar dates of the various months in different columns with no particular or definite position for the dates. With this arrangement an individual is unable to ascertain which 65 column contains the correct dates much less

the specific date without first knowing the day of the week. My improved calendar with its novel arrangement presents in plain view, at all times, in an upright position all the days of the week, the dates in a single 70 month with a positive indicating means which designates these dates and days of the week, thus making the calendar extremely efficient in operation.

In practice, I propose to cover the surface of the disc 19 with celluloid and thus bring the surface of the disc 19 in the same plane with the face on the disc 17, thereby providing a uniform and smooth surface to the face of the calendar. It is to be noted 75 that the wheel discs and dials constituting the calendar per se and the calendar mechanism are exceedingly thin with the whole thickness ranging from three-sixteenths to five-sixteenths of an inch, and the entire 80 weight of the calendar hardly exceeding one ounce. The fore-part of the extension and the hour hand weigh approximately the same as the calendar on the opposite end and, accordingly, the combination of the 85 hour hand and the calendar forms an almost perfect balance on the stub or axle of the hour hand thereby requiring but a minimum of force to rotate the same about the face of the clock and eliminating any danger of 90 retarding the movement of the hour hand by excess weight.

From the foregoing description considered in connection with the accompanying drawings, it will be noted that I have devised a 100 novel and useful calendar arrangement which will operate entirely by the action and force of gravitation wherein every single movement of any of the parts of the calendar is alone propelled by the force of gravitation. 105

It is to be understood that the form of my invention herewith shown and described is to be taken as a preferred example of the same and that various changes in the shape, 110 size and arrangement of parts may be resorted to without departing from the spirit of the invention or the scope of the subjoined claims.

Having thus described my invention, I 115 claim:—

1. In combination with a clock, a calendar, means for securing the calendar to the hour hand of the clock, said calendar embodying in its construction a day disc and a date disc, gravity actuated means positioned rearwardly of the calendar and including a meshing internal and external gear supported on the calendar securing means, a weight element carried by one of said gears, and an indicator carried by the other of said gears, substantially as and for the purpose described. 120

2. In combination with the hour hand of a clock, a calendar, supporting means for the 125 calendar connected to the clock hour hand, 130

said means including a substantially rectangular strip, a pintle positioned in one end of said strip and securing elements formed adjacent the opposite end of said strip for 5 embracing the clock hour hand, an internal and external gear positioned on the pintle and disposed rearwardly of the calendar, a weight element carried by the internal gear, an indicator carried by the external 10 gear and rotatable therewith for registering on the face of the calendar fixed periods of time corresponding to the movement of the hour hand about the face of the clock.

3. In combination with the hour hand of a 15 clock, a calendar embodying in its construction a day disc a date disc in frictional contact and having indicia thereon, means for securing the calendar to the clock hour hand, an external and internal gear having their 20 teeth in mesh and positioned rearwardly of said calendar and carried by the calendar securing means, an indicator connected to said external gear, a weight element carried by said internal gear, and co-operating with 25 the external gear for causing the indicator to register with the indicia of the calendar, whereby fixed periods of time will be indicated as the hour hand travels about the face of the clock.

30 4. In combination with the hour hand of a clock, a calendar, means for securing the cal-

endar to the hour hand of the clock, a plurality of indicia bearing discs detachably secured to the face of the calendar, gear mechanism positioned rearwardly of the calendar 25 and supported by the calendar securing means, an indicator carried by the gear mechanism, and gravity controlled means carried by the gear mechanism for actuating the indicator whereby fixed periods of time will be 40 registered on the indicia of the detachable discs as the hour hand travels about the face of the clock.

5. In combination with the hour hand of a clock, a calendar, weight means carried by 45 the calendar for retaining the same in an upright position, means for securing the calendar to the clock hour hand, a plurality of indicia bearing discs detachably secured to the face of the calendar, gear mechanism positioned rearwardly of the calendar and supported by the calendar securing means, an indicator carried by the gear mechanism, and gravity controlled means carried by the gear mechanism for actuating the indicator 50 whereby fixed periods of time will be registered on the indicia of the detachable discs as the hour hand travels about the face of the clock.

In testimony whereof I affix my signature.

GERALD MASON VAN DYKE.
